UNITED STATES PATENT OFFICE.

CHARLES F. HAWK, OF AKRON, OHIO.

PIANO-BENCH.

1,176,054.

Specification of Letters Patent. Patented Mar. 21, 1916.

Application filed December 13, 1913. Serial No. 806,366.

To all whom it may concern:

Be it known that I, CHARLES F. HAWK, a citizen of the United States, residing at Akron, in the county of Summit and State 5 of Ohio, have invented certain new and useful Improvements in Piano-Benches, of which the following is a specification.

My invention relates to improvements in piano benches, and the improvement comprises the construction and arrangement of parts substantially as herein shown and described and more particularly pointed out in the claims.

The object of the invention is to provide 15 a piano bench with a hinged cover or top adapted to be used as a seat and which may be opened to uncover a shallow receptacle for sheet music or other articles, and a further object is to provide this cover 20 with means to raise and lower the same to different elevations to accommodate the convenience or necessity of different persons in playing a piano or a player piano. The seat elevating means is also particularly designed to close the gap at the rear of the 25 seat when elevated and which would be unsightly and unfinished if open, and said means is also constructed to afford a secure stable seat when elevated. The seat elevating mechanism may be attached to any 30 standard piano bench having a top receptacle, and this is of decided advantage to manufacturers of piano benches as their present benches may be made into convertible 35 benches without reconstruction or change in design or style.

In the accompanying drawing, Figure 1 is a perspective view of a piano bench embodying my improvement, although the 40 bench, when closed as shown, is the same in appearance as a style or kind now before the public. Fig. 2 is a longitudinal vertical section of the bench with the seat lowered, but the legs of the bench are broken 45 away and the central portion of the bench is also shown as removed to permit the mechanism within to be shown about half size. Fig. 3 is a cross section on line 3—3, Fig. 2, the cover or seat being partly lifted 50 in dotted lines to indicate the hinge movement. Fig. 4 is a horizontal section in plan on line 4—4, Fig. 3, of one end of the bench. Fig. 5 is a perspective view of the bench 55 with the seat elevated and as the bench appears from the rear when placed before a piano as in use. Fig. 6 is a cross section

similar to Fig. 3 except that the cover is elevated front and rear and at an inclination for use with a player piano.

The bench comprises a shallow receptacle 60 2 mounted on legs 3 and provided with a hinged cover 4 adapted to provide a seat. The dimensions and style of this bench may vary. Ordinarily, the cover 4 is hinged directly to the receptacle 2, but in my invention the cover 4 is hinged to the front end of the head 5 of a stem or standard 6 which is slidably mounted in a vertical guide or support 7 affixed to the inside wall of the front board 8 of the receptacle. Head 70 5 projects over the top edge of the board, which is notched at 9 to seat the head when lowered, and the object in thus extending the seat hinge forwardly is to permit the cover to be raised and to turn without interference with the front board, especially 75 when the parts are in their lower positions of rest as in Fig. 3. It is customary to use a chain or link to limit the opening movement of the cover, and I may employ this 80 common expedient for the same purpose if it is found necessary or desirable.

The means to elevate and lower the cover and to positively support it in elevated position at both the front and rear sides of 85 the bench comprises a pivoted member 10 at each end of the bench at the rear thereof within receptacle 2 and these members are rigidly united at their free ends by a bar or strip 11 which is preferably made of 90 the same wood or finished to correspond to the rear board 12 of the receptacle 2 so that when raised to seat upon the upper edge of rear board 12 as seen in Fig. 6, the appearance of the bench will be slightly and 95 in keeping with the design or style as a whole. The length of the strip or connecting bar 11 is also preferably equal to the length of the bench, but in order to avoid recessing or notching the end boards 13 of 100 the receptacles to permit the lowering of the strip 11 below the top level of the receptacle 2 I prefer to shorten the strip, more or less, see Fig. 5, so that the strip 105 may be lowered into the receptacle into rest position on the cross walls 14, see Fig. 3. The width of the strip 11 or the length 110 of the pivoted members 10 determines the height to which the rear portion of cover 4 may be placed at rest, and this elevation is preferably fixed above the front portion of the cover as raised by standard 6 to es-

tablish an inclined seat and better foundation in operating the pedals of a player piano. However, this inclination is not an arbitrary requirement and the elevating and supporting parts for the seat may be otherwise proportioned to place the seat horizontal or on a level.

Elevation of the front portion of the cover or seat 4 is accomplished by engaging strip 11 by hand when cover 4 is raised and out of the way, and by imparting a turning movement to members 10 from a substantially horizontal position to a vertical position, see Figs. 3 and 6. This movement is utilized to rotate a bell-crank 15 pivoted at 16 upon the side of each cross wall 14 at the front of the receptacle, and which bell-crank has its upright arm connected to member 10 by a link 17. A lug 18 on the side of cross wall 14 serves as a rest or stop for said bell-crank, and the horizontal arm of the bell-crank is pivotally connected by a short link 19 with head 5 of standard 6. When the bell-crank 15 is turned to rest position against lug 18, the pivot connection 20 of link 19 with the bell-crank is thrown beyond the dead center line between pivot 16 and the head and link pivot 21, see Fig. 6. The result is that all the weight or pressure which is brought to bear upon the front portion of the seat or cover 4 when elevated will be positively and securely resisted and maintained by the associated parts. The rear portion of the seat is supported by the strip 11 the full length of said strip when seated on rear board 12, and the seat is stable and solid and will support as many persons as the length thereof will accommodate. The cross wall 14 is preferably a metal casting, but not necessarily, and it is made a removable or independent part of the receptacle to fit snugly therein between the rear and front boards and to be fastened thereto by screws or otherwise, and when in place these cross-walls divide the receptacle into two small end compartments 22 and one long middle compartment 23 which may be subdivided also if desired. The point is that the cross-walls not only brace and strengthen the receptacle body but also prevent the sheet music or other articles placed in the middle compartment from coming in contact with and interfering with the action of the operating parts fixed on the sides of the cross-walls 14. Moreover, the operating parts may be bodily removed from the receptacle without disconnecting

them or disturbing their fixed working relations on said cross-walls or with each other. Assembly of the bench is thus simplified and accurate fitting made easy without skilled labor. If desired, each end of the seat or cover may be provided with a depending strip or board 24 to come within the receptacle when the seat or cover is down, and to finish and conceal the working parts when the seat or cover is elevated, see Fig. 5.

What I claim is:

1. A piano bench having a seat, and elevating mechanism for the seat bodily replaceable jointly with the seat upon said bench comprising vertically slidable standards at the front of the seat and hinged thereto and a support for the rear of the seat hinged to the bench and operatively connected to said slidable standards.

2. A piano bench having a receptacle in its top, seat elevating mechanism mounted within the ends of said receptacle and operatively connected with the walls of said receptacle, and a seat hinged to said mechanism, the said mechanism comprising vertically slidable supports having hinged connection with the seat and a supporting board for the seat pivoted on the bench having link connection with said vertically slidable supports.

3. A piano bench having a seat and a seat elevating mechanism within the top thereof comprising slidable supports having heads hinged to said seat at the front thereof and a movable support for said mechanism adapted to provide a rest for the rear of said seat pivotally mounted on the sides of said bench and link and lever mechanism connecting the said rest with said slidable supports.

4. A piano bench having a seat, a vertically-movable standard having a hinged connection with said seat and operating connections for said standard comprising a movable part adapted to be raised to a vertical position to form a rest for the hinged end of the seat, and lifting means for the seat at the free end thereof, operatively connected by a link with said movable part for the standard.

In testimony whereof I affix my signature in presence of two witnesses.

CHARLES F. HAWK.
